UNITED STATES PATENT OFFICE.

MILDRED BLAKELY, OF PITTSBURG, PENNSYLVANIA.

IMPROVEMENT IN SKELPING-DIES.

Specification forming part of Letters Patent No. 70,397, dated November 5, 1867.

To all whom it may concern:

Be it known that I, MILDRED BLAKELY, of the city of Pittsburg, in the county of Allegheny and State of Pennsylvania, have invented a new and useful Improvement in Skelping-Dies; and I do hereby declare the following to be a full, clear, and exact description thereof.

Metal pipe other than such as is formed by the exudation of molten metal through properly-shaped dies, or by casting, is usually made by folding long sheets or strips of rolled metal, and welding the edges, where folded, together. This folding is usually done by drawing such sheets and strips through between the converging concave faces of a pair of skelping-dies, the two dies at the forward end, when closed together, having a front aperture of a nearly tubular shape. Such dies are made in two parts, with the plane of division running longitudinally and vertically through them, and the two parts are hinged together at the top. To operate them, it is necessary to open up the hinged die, introduce the metallic strip or skelp-bar from which the pipe is to be made so far that its forward end shall project somewhat beyond the forward end of the dies, close down the hinged die, to do which requires sufficient force to fold the skelp-bar to a tubular shape, and then, after properly fastening the movable hinged die, catch the projecting forward end of the skelp-bar with a pair of tongs and draw the bar through.

My invention relates to the construction of improved dies for the purposes above set forth; and consists in making a slot or opening in such dies along the line of division of the upper parts sufficiently large to admit the jaws of a pair of tongs. I then dispense with the hinging of one of the dies, make both fixed, catch the skelp-bar at the middle of one end with a pair of tongs, introduce it into the dies at the flaring end, and draw it through, passing the jaws of the tongs along the slot or opening in the upper part of the dies.

To enable others skilled in the art to make and use my invention, I will proceed to describe its construction and mode of operation, referring for that purpose to the drawings here-to annexed, in which—

Figure 1 is a perspective view of my improved skelping-dies, showing their construc-

tion and how used. Fig. 2 is a front view of the dies and skelp, showing the mode of making lap-weld pipe; and Fig. 3 is a similar view, showing the mode of making butt-weld pipe.

Like letters of reference indicate like parts.

A A are two dies, similar in shape and construction, securely fastened to any convenient bed or foundation, B. The dies are concave on their inner faces in the line of their cross-sections, of a nearly tubular shape in front, as at a, and flaring toward their rear ends, as at a'.

Along the top of the dies A A, or between them, and longitudinally therewith, I make a slot or opening, b, sufficiently wide to admit of the passage of the jaws c of a pair of tongs.

The skelp-bar d, being a flat sheet of metal of the proper width, is caught at or about the middle of one end by the tongs, introduced into the dies A A at the flaring end a', and pulled through, the tongs passing along the slot or opening b, as shown in Fig. 1. The force requisite to this is applied to the handles e e of the tongs in any convenient way, the tongs all the while retaining their grip on the skelp-bar d.

The edges of the bar d are, by the concave faces of the dies A A, folded down and under, so as to form a skelp, the edges of which, when welded together, give the pipe or tube required. In this way the skelp bars or blanks are passed through one after another as rapidly as may be desired.

The bottom part of the dies is made slightly different for forming butt or lap weld skelps, as may be required.

For a lap-weld the bottom edges of the dies A A are usually fitted neatly together, and by a finger or guide, properly inserted at any convenient point, one of the edges of the skelp s is made to overlap the other slightly, as shown in Fig. 2.

In dies for making a butt-weld skelp, a slot or opening is left between the dies on the bottom, and a tongue, i, Fig. 3, placed therein, which projects slightly upward, and against which the sides or edges of the skelp-blank s are bent, as in Fig. 3.

In either case the operation of the machine is substantially the same as is above described. The skelps, when made, are welded in the usual way.

The advantages I claim are a cheaper construction of dies, since both of the dies are fixed, and the cost of hinging is wholly obviated. The labor of forcing the hinged die downward after the blank is introduced is also saved.

With my invention no manual labor is required, except to catch the blanks with the tongs. As neither of the dies, when they are in use, requires to be moved, wear and tear are reduced to a minimum. I also produce a better skelp, since, with the ordinary mode of doing such work, the skelp bar or blank is apt to be kinked in closing down the hinged die, with consequent loss in the pipe when made.

The dies A A may be made separate or together, so as to form a single die, with two faces opposite each other. If made separate

they may be easily adjusted on the bed B, so as to form the skelp exactly of the proper size.

Having described my improvement, what I claim as my invention, and desire to secure by Letters Patent, is—

The construction and use of skelping-dies made either solid or separate, with a slot or opening, b, extending longitudinally along their upper part, through or between them, substantially as and for the purposes hereinbefore set forth.

In testimony whereof I, the said MILDRED BLAKELY, have hereunto set my hand.

MILDRED BLAKELY.
